UNITED STATES PATENT OFFICE

161,284

DARNING ATTACHMENT FOR SEWING MACHINES

Herbert H. Russell, New Haven, Conn., assignor to
The Greist Manufacturing Company, New
Haven, Conn., a corporation of Connecticut

Application May 9, 1950, Serial No. 9,825

Term of patent 14 years

(Cl. D70—1)

To all whom it may concern:

Be it known that I, Herbert H. Russell, a citizen of the United States, residing in New Haven, in the county of New Haven and State of Connecticut, have invented a new, original, and ornamental Design for a Darning Attachment for Sewing Machines, of which the following is a specification, reference being had to the accompanying drawing, forming part thereof, in which:

Fig. 1 is a front elevational view of a darning attachment for sewing machines embodying my new design;

Fig. 2 is a side elevational view thereof; and
Fig. 3 is a bottom plan view of the attachment.

I claim:

The ornamental design for a darning attachment for sewing machines, substantially as shown.

HERBERT H. RUSSELL.
